SPONGE AND LIQUID DISPENSER COMBINATION

Donald B. Schoenfield, Manhattan Beach, and Milton H. Schoenfield, Beverly Hills, Calif. (Both of 1417 S. Robertson Blvd., Los Angeles, Calif.)

Filed Apr. 15, 1965, Ser. No. 84,793

Term of patent 14 years

(Cl. D9—2)

FIGURE 1 is a perspective view of a sponge and liquid dispenser combination, showing the new design;
FIGURE 2 is a side elevational view thereof;
FIGURE 3 is a top view thereof;
FIGURE 4 is a front view thereof; and,
FIGURE 5 is a bottom view.
What is claimed is:
The ornamental design for a sponge and liquid dispenser combination, substantially as shown.
